Attorney

UNITED STATES PATENT OFFICE.

HAROLD E. WILLIAMS, OF CARTHAGE, MISSOURI.

FOLDABLE RACK.

Application filed July 9, 1925. Serial No. 42,576.

My invention relates to foldable racks adapted to be secured to the running boards of automobiles, and when opened or unfolded serving as guards for confining luggage that may be placed on such running boards. It has for its object to produce a rack of this kind that is of few parts, and is simple in construction and cheap to manufacture, but possesses ample strength and 10 rigidity when set up to serve all the purposes for which it is constructed.

In the drawings—

Figure 1 is a side view of the invention as applied to the running board of a car, 15 the parts being shown in the position they occupy when the rack is in use.

Fig. 2 is an elevation of the rack when folded.

Fig. 3 is a transverse vertical section taken 20 on the line III—III of Fig. 1.

Figure 4 is a bottom plan view of the rack when folded.

Referring to the drawings A indicates the body of an automobile, B the running board 25 thereof, and C the wheel fenders. The rack embodying my present invention is represented as secured to the edge of the running board, although it is adapted to be applied to other supports and to be used for other 30 purposes than that which has been indicated, as for instance as a guard for a platform or a shelf. For this reason I wish it to be understood that such terms a "running board," "luggage," etc., are used in a 35 typical sense, and not for the purpose of restricting the invention to a particular use.

The rack comprises a set of clamps adapted 40 to engage with the edge of the running board B, an upper longitudinal rail 3, and jointed foldable supports between each clamp and the rail. The rail is preferably angular in cross section and of a length somewhat greater than the distance between the clamps. The jointed links connecting 45 one end of the rail 3 with a clamp are designated 5 and 6, these being united to each other by the intermediate pivot 7, and to a clamp 2 and the rail 3, respectively, by the pivots 8 and 9. These two links are 50 preferably of the same length, so that the intermediate joint 7 is midway between the top rail and the clamp. The jointed links at the opposite end of the rack are designated 10 and 11, and these are united to each 55 other by an intermediate pivot 13, and are

connected respectively with a clamp 2 and the upper rail by the pivots 12 and 14. In order to maintain the upper rail always in parallelism with the edge of the board B, I interpose between the intermediate 60 joints 7 and 13 of the foldable supports for the upper rail, a stiff bar 4.

The arrangement described permits the rack to be unfolded with the upper rail elevated the desired distance above the board 65 B, as represented in Fig. 1, or folded with the rail 3 dropped to a position close to or opposite the edge of the board B.

In order to provide for rigidly holding the rack in its open or extended position, 70 and preferably in position with the jointed supports somewhat buckled, as represented, I extend one of the links that is pivotally connected with a clamp, the link 10 in the showing in the drawings, beyond its intermediate pivotal connection at 13, so as to 75 form an arm 10' of a length to reach the rail 3. This arm or extension is provided with a pin or stud 16 that is adapted to move in a slot 15 formed in the vertical member of the rail 3. The end of the slot nearest the pivot 14 is shaped to form a shouldered seat 17 in which the pin or stud 16 rests when the rack is extended, as 80 represented in Fig. 1. Whenever the pin 16 is seated in the recess 17 the parts of the rack are securely held in open or extended position, and will be thus maintained until the holding parts are manually released by 85 withdrawing the stud from its seat and permitting it to enter the smooth portion of the slot 15, in which it may slide as the parts of the rack move during the folding and unfolding operation. The rack being 90 extended and the parts thereof held locked in the open position as described, all that is required to be done to release and fold the rack is to lift the pin from its seat and press downward upon the top rail 3, and this will cause the supporting jointed links 95 to buckle or fold and the parts to assume the position represented in Fig. 2. To open the rack it is only necessary to lift up on the top rail, until the parts assume the 100 open position with the pin 16 in the seat 17 at the end of the slot 15.

What I claim is:

1. A rack comprising clamps by which it may be united to a running board, a longitudinal rail, foldable jointed supports con- 116

necting the rail with the clamps, each support consisting of a pair of rigid links respectively pivotally connected with the rail and with the clamps and pivotally united with each other, means directly connected with one of the links that is pivoted to a clamp and arranged to engage directly with the longitudinal rail for holding the rack in extended position, and an intermediate 10 bar connecting the foldable supports together at their intermediate joints.

2. A rack comprising an upper longitudinal rail, means for connecting the rack to a running board, foldable jointed supports 15 uniting the rail and the said connecting means, each consisting of a pair of links respectively pivoted to the rail and to the connecting means, and pivotally united with each other, a rigid intermediate bar connecting the jointed supports at their intermediate pivotal connections, and means interposed directly between the top rail and at

least one of the jointed foldable supports for holding the rack in extended position.

3. A foldable rack comprising a top longitudinal rail in which is a slot formed with a shouldered seat, means for uniting the rack to a running board, foldable jointed supports, each consisting of a pair of links, the lower link being pivoted to the means 30 by which the rack is united to its running board, and the upper link being pivoted to the top rail, the two links being pivotally united to form the intermediate joint of the support, a rigid bar uniting the supports at 35 their intermediate joints, and a rigid extension carried by the lower link of at least one of the supports and provided at its upper end with a stud adapted to move along the slot in the top rail and to occupy 40 the shouldered seat thereof in order to hold the rack in extended position.

HAROLD E. WILLIAMS.
